UNITED STATES PATENT OFFICE.

FRANK YOKEL, OF CLEVELAND, OHIO, ASSIGNOR TO MARKEL ELECTRIC PRODUCTS, INC., OF BUFFALO, NEW YORK, A CORPORATION OF NEW YORK.

DESIGN FOR A CEILING-PLATE ELECTRIC FIXTURE.

Application filed April 2, 1928. Serial No. 26,104. Term of patent 3½ years.

To all whom it may concern:

Be it known that I, FRANK YOKEL, a citizen of the United States, residing at Cleveland, in the county of Cuyahoga and State of Ohio, have invented a new, original, and ornamental Design for a Ceiling-Plate Electric Fixture, of which the following is a specification, reference being had to the accompanying drawing, forming part thereof.

In said drawing:

Figure 1 is a bottom plan design for a ceiling plate electric fixture embodying my new design.

Figure 2 is an elevation of the same.

I claim:

The ornamental design for a ceiling plate electric fixture, as shown.

FRANK YOKEL.
